UNITED STATES PATENT OFFICE.

CLAY T. STEWART, OF ROCHESTER, NEW YORK

MOTOMETER-LIGHTING ATTACHMENT.

Application filed December 10, 1925. Serial No. 74,546.

My invention relates to a motometer lighting attachment, and has for its object to afford a simple and practicable arrangement that is readily attachable to conventional styles of motometers, and functions to illuminate the liquid tube at night.

Another purpose of the improvement is to provide a unitary attachment that can be manufactured at a low cost, and quickly assembled in operative relationship upon a motometer.

Still a further object of the invention is to afford an arrangement that will illuminate the liquid tube of the motometer at night, at the same time protecting the eyes of a driver against glare or light coming directly from the illuminating means.

An additional object of the improvement is to afford a structure of few parts that can be housed within the conventional type of motometer so as in no way to interfere with the customary use of the latter or to detract from its appearance.

Another purpose of the improvement is to afford a construction that requires no supplemental attaching means, but can be held in place within a motometer by parts found in the conventional motometer construction.

With these and other ends in view, the invention comprises the structure that will appear clearly from the following description when read in conjunction with the accompanying drawings, the novel features being pointed out in the claims following the description.

In the drawings:

Figure 1 is a rear elevation of a conventional type of motometer showing the application of my improvement thereto;

Figure 2 is a similar view with the crystal and retaining plate removed;

Figure 3 is a front elevation of the attachment embodying my invention;

Figure 4 is an edge elevation of the same;

Figure 5 is a sectional view on the line 5—5 of Figure 3, and

Figure 6 is a sectional view on line 6—6 of Figure 3.

In the embodiment illustrated, which includes a preferred arrangement of the invention, 1 designates the housing of a conventional type of motometer including a liquid tube 2 and retaining ring 3 which holds in place the rear crystal, while 4 is the usual sight opening in the front crystal.

5 designates a support, preferably in the form of a plate shaped substantially as shown, although the support 5 may be constructed in other ways and accomplish the essential purposes of the invention. The support 5 is preferably curved along its outer edge, as indicated at 6, to conform to the housing 1 and retaining ring 3 of the motometer. The support 5 is held in place by being positioned as shown in Figure 2, after which the crystal retaining ring 3 is superposed upon the support 5, and the screws 7 which are used to hold the retaining ring 3 in place engage the openings 8 in the support 5 and thus retain the latter as indicated in Figures 1 and 2.

At its inner edge, the supporting plate 5 extends straight along a portion of the liquid tube 2 and parallel thereto, as indicated at 9, and above the straight portion 9 it is curved as indicated at 10, to conform to the sight opening 4, and leave the latter free for observation by the driver. The inner edges 9 and 10 of the supporting plate are provided with forwardly projecting flanges 11 and 12 which deflect the light from the lamp and prevent any glare or light striking the eyes of the driver.

13 designates a lamp socket which is attached to the front face of the supporting plate 5, preferably by soldering or otherwise permanently affixing a lug 14 which is secured to the lamp socket. 15 designates a conducting member also connected to the lamp socket and preferably in the form of a flat strip adapted to extend under the retaining ring 3, as shown in Figures 1 and 2. The flat conducting strip 15 terminates in a switch socket 16 which is preferably but not necessarily of flat formation and adapted to receive a switch plug 17 of a conductor 18 which leads to a battery or suitable source of power.

The construction described is of extreme simplicity, and has the advantage of comprising but a single unit which can be quickly attached in proper position in a conventional motometer by merely removing the retaining ring and rear crystal of the latter to permit of placing the supporting plate 5 under the retaining ring, as shown in Figures 1 and 2. Upon repositioning the crystal and retaining ring and securing the latter in place, the illuminating attachment is ready for operation when connection is made through the plug 17.

The invention is not restricted to the precise details herein illustrated, and this application is intended to cover other modifications and changes such as may come within the spirit of my improvement or the scope of the following claims.

I claim:

1. A motometer lighting attachment comprising a removable supporting plate, a lamp socket secured to the front face of the supporting plate, and a flat conducting strip connected to the lamp socket and terminating in a switch socket adapted to be located outside the motometer, said supporting plate serving to shield the eye of a driver from the lamp.
2. A motometer lighting attachment comprising a supporting plate, a lamp socket permanently attached to one face of said plate, and light deflecting flanges along the inner edges of the plate.
3. A motometer lighting attachment comprising a supporting plate, a lamp socket permanently attached to one face of the plate, light deflecting flanges along the inner edges of the plate, and a flat conducting member connected to the lamp socket and terminating in a switch socket adapted to be located outside the motometer.
4. The combination with a motometer including a retaining ring for a rear crystal, of a supporting plate removably held in position by the retaining ring and arranged in a plane parallel thereto, a lamp socket secured to the front face of said plate, and a conducting member connected to the lamp socket and extending under the retaining ring and terminating outside the motometer in a switch socket.
5. The combination with a motometer including a retaining ring for a rear crystal, of a supporting plate, the outer edges of the supporting plate being curved to conform to the retaining ring and held in place thereby, the inner edge of said plate extending parallel to the liquid tube for a portion of the latter and curving thence around the sight opening, a lamp socket permanently attached to the front face of the plate, and a conducting member connected to the lamp socket and extending under the retaining ring, terminating outside the motometer in a switch socket.
6. The combination with a motometer including a retaining ring for a rear crystal, of a supporting plate, the outer edge of the supporting plate being curved to conform to the retaining ring and held in place thereby, the inner edge of said plate extending parallel to the liquid tube for a portion of the latter and curving thence around the sight opening, forwardly projecting light deflecting flanges along the inner edges of the plate, a lamp socket permanently attached to the front face of the plate, and a flat conducting member connected to the lamp socket and extending under the retaining ring, terminating in a flat switch socket.
7. The combination with a motometer including a retaining ring for a rear crystal, of a plate removably held in place by the retaining ring and arranged in a plane parallel thereto, and a lamp socket carried by the plate, said plate functioning both to support the lamp socket and to shield the eyes of a driver from light cast by a lamp in said socket.
8. The combination with a motometer including a retaining ring for a rear crystal, of a support located within the motometer and removably held in place by said retaining ring, and a lamp socket attached to the forward face of the support, the latter comprising a plate arranged in rear of a lamp socket and functioning to shield the eyes of a driver from light of the lamp.

In witness whereof, I have hereunto signed my name.

CLAY T. STEWART.
